DESIGN FOR A COMBINATION CENTRIFUGAL SEPARATING MACHINE CASING AND BASE

Joseph S. Pecker, Philadelphia, Pa., assignor to
American Centrifugal Corporation, New York,
N. Y., a corporation of Delaware

Application February 2, 1937, Serial No. 67,410

Term of patent 14 years

To all whom it may concern:

Be it known that I, Joseph S. Pecker, a citizen of the United States, residing at Philadelphia, in the county of Philadelphia and State of Pennsylvania, have invented a new, original, and ornamental Design for a Combination Centrifugal Separating Machine Casing and Base, of which the following is a specification, reference being had to the accompanying drawings, forming part thereof.

In the drawings:

Fig. 1 is a plan view of the base of the combination centrifugal separating machine casing and base.

Fig. 2 is a front elevation of the combination centrifugal separating machine casing and base.

Fig. 3 is an end elevation of the same.

I claim:

The ornamental design for a combination centrifugal separating machine casing and base as shown and described.

JOSEPH S. PECKER.
